US0D1064998S

(12) **United States Design Patent** (10) **Patent No.:** **US D1,064,998 S**
(45) **Date of Patent:** **** Mar. 4, 2025**

(54) **WHEEL FOR VEHICLES**

(71) Applicants: **Hyundai Motor Company**, Seoul (KR); **Kia Corporation**, Seoul (KR)

(72) Inventors: **Dae-Chul Jang**, Gyeonggi-do (KR); **Hyun-Doo Lee**, Seoul (KR)

(73) Assignees: **Hyundai Motor Company**, Seoul (KR); **Kia Corporation**, Seoul (KR)

(**) Term: **15 Years**

(21) Appl. No.: **29/898,444**

(22) Filed: **Jul. 27, 2023**

(30) **Foreign Application Priority Data**

Feb. 10, 2023 (KR) 30-2023-0004884
